METHOD AND APPARATUS FOR OPERATING
INTERNAL COMBUSTION ENGINES

William E. Leibing, Sausalito, Calif.

Application February 26, 1935, Serial No. 8,378

16 Claims. (Cl. 123—52)

This invention relates to a novel method of operating internal combustion engines and novel apparatus to be associated therewith. More particularly my invention relates to a method of and apparatus for the control of the feed of fuel thereto for effecting the efficient operation of internal combustion engines whereby the discharge therefrom of obnoxious, unhealthy and unburned vapors and gases is prevented.

10 In the operation of the existing types of internal combustion engines, as for instance in connection with buses, trucks and other heavy duty vehicles, the relatively low compression pressures existing in the cylinders at idling speed are insufficient for the proper burning of the charges of fuel being fed thereto at the corresponding speed. This is apparent from the manner in which an engine of the type noted will foul up if left at idling speed for any extended period of time.

15 Likewise, the lack of compression which exists in an engine of a bus or truck when the throttle is closed at high speed and the vehicle drives the engine, and also the shorter period of time in which the charge must burn, are entirely inadequate for anything approaching complete combustion.

20 Under both the above mentioned circumstances gassing or a discharge of unburned vapors or gases from the exhaust of the engine occurs which is not only wasteful, but also obnoxious and undesirable from a health standpoint. This is highly undesirable particularly in buses where large numbers of passengers are carried and frequent stopping and starting is necessary in traffic congested districts.

25 In overcoming these disadvantages of prior methods of operation, it is a primary object of the present invention to provide a novel method and apparatus whereby the relatively low compression pressures afore-mentioned are raised to a point where the fuel charges fed thereto are completely burned with resulting economies in operation, and no discharge of unhealthy and obnoxious gases and vapors.

30 35 I have found this may be done in the present invention in a multi-cylinder engine by removing one or more of the cylinders from the working class and converting them to air compressors only, whereby the compression pressure in the remaining cylinders is greatly increased with no increase in idling speed by reason of the lesser number of working cylinders and the work or effort required of the same to drive the cylinders converted to air compressors.

40 45 50 55 It will be noted that the work of the cylinders

converted to air compressors is entirely unlike that of the conventional air compressor wherein the air is exhausted at the end of the compression stroke and there is no driving effect from the air so compressed. Since all the valves of an internal combustion engine remain closed at top dead center following the compression stroke, the work required to compress the air on the compression stroke is virtually all returned to the engine by the expansion of the compressed air itself on the reverse stroke. The pumping out of such air into the exhaust system is done against atmospheric pressure only. Therefore the net expenditure of work of the engine when used as an air compressor is that lost due to friction and due to the heat of compression.

5 10 15 20 25 30 35 While it might be assumed that poor economy and roughness of operation would result from the operation of a number of cylinders as air compressors with the remaining cylinders carrying on the work, it has been found in practice that the economy and smoothness of operation are improved and substantial savings are effected since the expansion of the compressed air prevents roughness, and since in place of the full number of the cylinders of the engine working under low compression and hence under unfavorable conditions in the usual idling operation, there is a lesser number of cylinders working under far better conditions in my improved arrangement.

40 45 50 55 While the foregoing method has been described as of advantage in only two conditions of engine operation, it can also be employed to advantage when an engine is not doing useful work or when operating under light loads.

The engine cylinders, so converted, are preferably opened to air or a like non-combustible gas at atmospheric pressure or at a pressure sufficiently high to avoid the creation of a relatively high vacuum in the cylinders. Otherwise, the converted cylinders at the high vacuum would tend to foul by reason of the suction of oil past the pistons with little or no pressure to force the oil back to the crank case. By the elimination of the vacuum, there is no tendency to such oil from the crank case past the pistons and the compression in the cylinders effectively keeps the cylinders and spark plugs from fouling with oil.

A further object of this invention is to provide a novel method and means whereby an internal combustion engine, under conditions normally producing gassing, has the exhaust system including the muffler and associated equipment thoroughly purged by the forced circulation of pure air or other suitable medium.

Still a further object of this invention is to provide a novel method and means whereby an internal combustion engine under conditions normally producing gassing, has the exhaust system purged by the forced circulation of pure air or other suitable medium.

Another object of the present invention is to provide novel means for controlling the supply of fuel and air to an internal combustion engine in such a manner that the fuel mixture is supplied to all of the cylinders during the time that the engine is pulling a load and to only certain cylinders during shifting, coasting, braking and like operations.

A further object of the present invention is to provide a novel linkage, operable upon actuation of the throttle of an internal combustion engine which is adapted to close auxiliary air inlets prior to the opening of the main throttle valve and auxiliary fuel cut-off valves, and permits closing of the latter valves prior to the opening of the auxiliary air inlets.

Another object of the present invention resides in the provision of means for automatically controlling the supply of fuel and air to an internal combustion engine in accordance with the intake vacuum pressure in such a manner that fuel mixture is supplied to all of said cylinders when the intake vacuum is below a certain predetermined value and to only certain of the cylinders when the intake vacuum rises to or above said predetermined value.

A further object of the present invention is to provide an internal combustion engine intake manifold with valves which are designed to interrupt the supply of fuel to certain cylinders and supply pure air thereto under other conditions.

Still further objects of my invention will appear as the following detailed description proceeds in conjunction with the appended claims and attached drawings wherein:

Figure 1 is an elevational view showing a novel manifold and linkage utilized in one form of the present invention for controlling the valves provided in the manifold.

Figure 2 is an enlarged transverse sectional view taken on line 2-2 of Figure 1 showing one of the valves of Figure 1 and the slip joint used to obtain the desired operation of said valve.

Figure 3 is an elevational view of the end of the valve shaft of Figure 2 showing the relative position of the shoulders of the slip joint used thereon.

Figure 4 is an enlarged sectional view on line 4-4 of Figure 1 showing the shaft and slip joint used on the auxiliary air valves shown in Figure 1.

Figure 5 is an elevational view of the end of the shaft shown in Figure 4 showing the relation of the shoulders of the slip joint shown in Figure 4.

Figure 6 is an elevational view showing a modified form of the invention with the manifold broken away in part in order to more clearly illustrate the device.

Figure 7 is a longitudinal sectional view of the end section of Figure 6 showing the detailed arrangement of the valves and actuator.

Figure 8 is a transverse sectional view taken on line 8-8 of Figure 6 and shows the means for supporting the actuator and the transverse relation of the actuator and valves.

Figure 9 is an elevational view, partially in section, of a modified form of the invention wherein an automatic pressure responsive actuator is utilized to replace the throttle connected actuating linkage of the other forms of the invention.

With continued reference to the drawings wherein like reference characters designate the same parts throughout the several figures, as shown in Figure 1, 10 indicates generally an intake manifold embodying the present invention. Manifold 10 is provided with a depending portion 11 which is provided with an annular flange 12. A carburetor 13 of any desired known make having a flange 14 may be secured to flange 12. A gasket 14' is disposed between flanges 12 and 14 which are secured together by bolts or studs 15.

Manifold 10, as shown in the drawings, is adapted for a six cylinder internal combustion engine, and is provided with three outlet branches 16, 17 and 18. Each branch 16, 17, and 18 is provided with a flange 19 adapted to be secured in any suitable manner to the intake ports of the internal combustion engine cylinders. The manifold illustrated supplies fuel to two of the cylinders of the engine through each branch. Branch 16, for example, may supply cylinders numbered 5 and 6, branch 17 may supply cylinders numbered 3 and 4, and branch 18 may supply cylinders numbered 1 and 2 as in the well known "Twin Coach Hercules" engine.

Carburetor 13 is provided with the usual butterfly control valve 21 adapted to control fuel admission through passage 22 thereof. Valve 21 is carried by a shaft 23 extending across passage 22 and journaled in suitable bosses in the wall 24 of passage 22. The projecting end of shaft 23 is an operating bell-crank 25 which has an arm 26 integrally formed thereon. Arm 26 is suitably threaded to receive an adjustable stop screw 28 adapted to abut a projection 29 integrally formed on the exterior of wall 24. Stop 28 functions in a manner to be hereinafter pointed out. The manifold illustrated in the drawings is of the well-known "hot spot" type, and numeral 30 indicates the structure forming the "hot spot".

Manifold 10 as illustrated in the drawings is made up of a plurality of sections. A center section 34 is provided and depending portion 11 is formed as an integral part thereof. Section 34 is also provided with securing flanges 35 which are adapted to be secured to flanges 36 of intermediate sections 37 by suitable bolt assemblies 38. A gasket 39 is disposed between sections 34 and 37 to provide a fluid tight joint between these parts.

Sections 37 adjacent flanges 36 are provided with butterfly valves 41 which are carried by suitably journaled shafts 42 and 42'. Valves 41 are adapted to be operated in a manner to be presently described to completely close passages 43 of sections 37, to prevent passage of the fuel mixture from the carburetor to branches 16 and 18 of the manifold during predetermined operating periods and throttle positions of the internal combustion engine. The purpose of these valves will be described in greater detail as the description of the device proceeds.

Sections 37 are also provided with downwardly extending auxiliary air conduits 44. Passages 45 of conduits 44 are in direct communication with passage 43 at points between valves 41 and branches 16 and 18 as clearly shown in the drawings. Butterfly valves 46 carried on suitably journaled shafts 47 are disposed in conduits 44 for the purpose of connecting the passage 43 directly to the atmosphere at all times when the valves 41 are in position to prevent a flow of fuel to outlet branches 16 and 18 of the manifold. Suitable flanges 48 formed on sections 37 are secured to

flanges 48 of end sections 51. Gaskets 52 are disposed between flanges 48 and 49 in order to provide a fluid tight connection at this point. Bolts or studs 53 secure sections 37 and 51 in assembled relation. Suitable air cleaners 54 of any well-known construction are provided for conduits 44 and the carburetor air intake 50.

The operating mechanism for the various control valves comprises an operating lever 55 journaled on shaft 23, a bell-crank 56 journaled on shaft 42, and a lever 57 journaled on a shaft 42'. Each of these levers is adapted to rotate its respective shaft and the valves 21 and 41 through identical drive connections, only one of which will 10 now be shown in detail. As shown in Figure 2, these drive connections comprise a shoulder 58 on each of said levers adapted to engage shoulders 59 formed on collars 60 secured to each of the shafts 23, 42, and 42' respectively by pins 61, and so arranged that as the respective levers are rocked in a clockwise direction from the position shown in Figure 1, the respective shafts and the valves 21 and 41 carried thereby are rotated in a clockwise direction.

25 Bell-crank 56 is provided with arms 62, 63, and 64, arm 63 being preferably equal in length to arm 57. Arm 62 is connected by means of pin 65 to clevis 66 of an adjustable connecting link 67, the opposite clevis 68 of which is connected by a pin 69 to the end of operating lever 55 for throttle valve 21. Also connected to arm 55 by means of pin 69 is the clevis 70 of the usual throttle operating rod 71 actuated by the usual engine controlling accelerator (not shown). Rod 71 is normally urged to the left in Figure 1 by means of a restoring spring 72, secured at one end to extension 73 of rod 71, and at its opposite end to a suitable stationary support 73', in well-known manner.

40 An operating rod 74, adjustably connected to clevis 75 which is in turn secured to arm 63 of bell-crank 56 by means of a pin 76, interconnects arms 63 and operating arm 57 of shaft 42' through clevis 78 secured to arm 57 by means of a pin 79 and adjustably connected to the opposite end of rod 74.

The linkage so far described will rotate valves 21 and 41 in a clockwise direction only in Figure 1. To rotate valves 21 and 41 in the opposite direction coil-like restoring springs 81 are provided for each shaft. As shown in Figure 2 springs 81 surround the ends of shafts 23, 42 and 42' opposite to that upon which collars 60 are mounted. Coil springs 81 are provided with longitudinally extending tips 82 and 83. Tips 82 enter into recesses 84 provided in bosses 85 integrally formed on wall 24 of the carburetor and the walls of sections 37. Tips 83 engage pins 86 suitably secured in or formed on the ends of shafts 23, 42 and 42'. As shown in Figure 2 the springs 81 are arranged in such a manner that they are wound up upon rotation of shafts 23, 42 and 42' in a clockwise direction under the influence of levers and collars 60. As a consequence of this winding up of springs 81, shafts 23, 42 and 42' are rotated in a counter-clockwise direction upon release of rod 71.

70 Springs 81, when the valves and linkage are disposed in their idling position, are adapted to exert a sufficient counter-clockwise force to retain the valves 21 and 41 in closed position. Since shoulders 58 and 59 are not connected, levers 55 and 57 and bell-crank 56 may be rotated in a counter-clockwise direction after valves 21 and 41 are completely closed without any movement of shafts 23, 42 and 42', and without binding of the linkage.

5 Arm 64 of bell-crank 56 and lever 57 are each provided with a pin 87 securing like clevises 88 thereto at equal distances from shafts 42 and 42'. Clevises 88 adjustably receive operating rods 89 which are secured by clevises 90 and pins 91 to the ends of levers 92 which are journaled on the ends of shafts 47. Each lever 92 is provided with a shoulder 93 (Fig. 4) which is adapted to engage a shoulder 94 provided on collar 95 rigidly secured to each shaft 47 by a pin 96. Shoulders 93 and 94 are so constructed that upon clockwise movement of levers 92 no movement of shafts 47 will result, while upon counter-clockwise movement of levers 92, shoulders 93 and 94 will engage and cause a counter-clockwise rotation of shafts 47 and their 10 associated valves 46.

15 Shafts 47 are provided with coil springs 99 (Fig. 4), similar in construction to springs 81. Springs 99 are provided with longitudinally extending tips 101 and 102. Tips 101 extend into 20 recesses 103 formed in bosses 104 integrally formed on the walls of members 44. Tips 102 engage pins 105 secured in suitable manner at the end of shafts 47. Springs 99 are designed to bias shafts 47 and valves 46 to closed position, or to 25 rotate them in a clockwise direction as viewed in Figure 1.

30 Since links 89 are secured to bell-crank 56 and lever 57 respectively, it will be seen that, upon operation of rod 71 and rods 67 and 74 as hereinbefore described, rods 89 and levers 92 will be rotated in a clockwise direction. In view of this fact it will be appreciated that springs 99 only need be strong enough to close valves 46. The entire operating linkage, it will be seen, is restored under the influence of the springs to the position shown in Figure 1, when rod 71 is released with the adjustable stop screw 25 mounted on stop extension 26 of throttle operating lever 51, engaging stop member 29 which is supported from 35 the carburetor body.

35 The linkage is so adjusted, and the slip joint connections thereof to the valves are such in operation, that on initial movement of the accelerator controlled rod 71 from the idling position the air inlet valves 46 are completely closed before the shoulders 58 of levers 55, 56, and 57 engage shoulders 59 of collars 60. After valves 46 are closed, further movement of the linkage causes the shoulders 58 of levers 56 and 57 to engage their collar shoulders 59, opening valves 41. 40 After valves 41 are opened the shoulder 58 of lever 55 engages its collar shoulder 59, and throttle valve 21 is then opened and operated in the usual manner to control the engine speed with 45 the manifold under normal conditions. When the accelerator pressure is released it will therefore be seen that the operation of the valves will occur in reverse order, throttle valve 21 being first closed, after which valves 41 will close, and 50 then valves 46 will open. It will therefore be seen that the normal function of the motor is 55 not disturbed in any way.

Idling operation

55 With the parts in idling position as shown in Figure 1, fuel is supplied from idling jet 109 of the carburetor to branch 11 of the manifold only, due to the complete closure of the passage 48 by valves 41. Under these conditions the branches 70 16 and 18 of manifold 10 will not be supplied with fuel and no combustion can take place in cylinders numbered 1, 2, 5, and 6. Since the firing order of the cylinders of the particular motor illustrated is 1-5-3-6-2-4, it will be seen

that cylinders 3 and 4, which are supplied with fuel by branch 17 of manifold 10, are directly opposite each other in the firing order.

The engine will accordingly be driven by cylinders 3 and 4 alone, and, as the crankshaft rotates, cylinders 1-5-6 and 2 will continue their cycle of operation drawing pure air only through conduits 45 and outlet branches 16 and 18 during their suction stroke. This air is compressed on the compression stroke, and then expands on the power stroke imparting driving power to the pistons. On the exhaust stroke of each cylinder it is then forced out giving a complete air scavenging of each of these cylinders during each cycle of operation.

Due to the direct connection to the atmosphere at this time there will be no tendency for a low pressure to exist in the ends of manifold 10. As a consequence it will be seen that the suction created by cylinders 3 and 4 is the only suction available for withdrawing fuel from the carburetor, and the fuel withdrawn from the carburetor at idling speeds will therefore be materially reduced from that used in prior idling operations.

While it may at first appear that an engine, operating in the above disclosed manner, would fail to run due to the inoperativeness of the major number of its cylinders, it has been found that its operation is equally as good if not better than the prior idling operation. This result is due to the fact that the compression in cylinders 3 and 4 is increased with the result that combustion is complete. The increased power resulting therefrom, due to the more complete combustion of the fuel, together with the expanding action of the air compressed in cylinders numbered 1, 2, 5 and 6 during their power strokes, causes the engine to run more smoothly than is the case when all of the cylinders are operating under reduced compression pressures.

With a six cylinder motor having a 300 cu. inch displacement and a possible 5 to 1 compression ratio (determined by the ratio of the clearance space to the full cylinder volume) and the novel manifold of the present invention in place, the manifold vacuum during idling operation was reduced from 20 inches (with the conventional manifold) to 8 inches. With 8 inches vacuum existing in the intake manifold the compression ratio was increased to 3.6 to 1 and the charge drawn into the cylinders was found to be 11/15 or better than $\frac{2}{3}$ of the full charge. This equals 22,000 cu. inches per minute of mixture. The time permitted for the burning of the fuel at 400 R. P. M. still being 1/800 of a minute and the compression ratio being 3.6 to 1 complete combustion resulted and the exhaust was composed of substantially completely burned gases. The pure, fresh air exhausted from the four cylinders which were not supplied with fuel mixed with the exhaust from the active cylinders at the rate of 48,000 cu. inches per minute, to thereby further reduce the gassing. The obnoxious gassing resulting from the use of the conventional form of manifold was therefore largely eliminated by the complete combustion and introduction of pure fresh air.

The large volume of pure air being drawn through the cut-off cylinders at idling also purges the cylinders of gases and the like and cleans out the exhaust system. Since the cylinders, which are not being used in the conventional manner, are vented directly to the atmosphere through relatively large ports, there is a

total absence of vacuum existing in the ends of the manifold and there will be no tendency for the oil in the crankcase to be sucked past the pistons. The idle cylinders and the associated spark plugs will therefore not become gummed up with oil in the manner incident to conventional motor operation with the consequence that their proper operation is assured.

Decelerating operation

In addition to its functions as a degasser, cylinder and exhaust purger, my invention effects a marked saving of fuel. This follows due to the fact that the engine with the conventional manifold drew 30,000 cu. inches of mixture per minute, a quantity of which was exhausted in an unburned or partly burned condition, whereas with the manifold of the present invention, the engine drew only 22,000 cu. inches of mixture per minute and the mixture so drawn was completely burned. Therefore a reduction of 8,000 cu. inches per minute in the amount of fuel consumed at idling was effected by the present invention and due to the raise in compression and consequent raise in efficiency approximately a 50% saving of the normal idling fuel requirements has been accomplished in actual tests with the device.

My invention is also effective as a degasser and fuel economizer, and to provide improved engine braking during the periods when the vehicle is coasting or being decelerated with the engine connected to the driving wheels. During such periods of motor operation due to its momentum, the vehicle frequently drives the engine at a speed much higher than idling speed with the throttle closed. The intake manifold vacuum under these conditions goes considerably above the idling vacuum, with the usual manifold constructions. This results in even worse combustion and worse gassing than that which occurs during idling operation.

With the novel manifold construction of the present invention installed, the engine during deceleration received a fuel charge in only two cylinders as described in connection with the idling speed of the engine. The speed of the engine being 2,000 R. P. M. during deceleration only 1/4000 of a minute was allowed for combustion of the fuel. However, since only two cylinders were effective for drawing fuel from the carburetor, the intake vacuum was found to be about 10 inches instead of 26 inches, as was found to be the case with a conventional manifold. The fuel supply was reduced to about 110,000 cu. inches per minute, about a 30% saving. The ratio of increase in compression under the above mentioned conditions was found to be about 3.2 to 1. This increase in compression resulted in practically complete combustion of the fuel mixture supplied to cylinders 3 and 4.

The remaining cylinders during deceleration act to draw pure air through the auxiliary air ports and exhaust it through the exhaust system at a rate of approximately 240,000 cu. inches per minute. This pure air purges cylinders 1, 2, 5, and 6 and mixes with the completely burned exhaust from cylinders 3 and 4. Since the exhaust from the operative cylinders contains little or no noxious gases, the addition of the large quantities of pure air thereto results in an exhaust which is practically free from obnoxious gases. In addition to the advantage of the pure exhaust, it will be apparent that a considerable saving of fuel is also effected during deceleration.

Modified forms of invention

In Figure 6 a modified form of my invention is shown. Since the parts at each end of the manifold in this form are for the most part duplicates, only one end is shown in complete detail in the drawings. Parts similar to those heretofore described have been designated by like reference characters and reference to the foregoing description may be had for a complete understanding of such parts. In this form of the invention the center section 34a is longer and the manifold is made up of fewer parts, the slip joints described in connection with the modification shown in Figures 1 to 5 are eliminated, and the successive operation of the several valves is effected through the use of different types of lost motion connections and a novel internal cam structure.

As shown in Figure 6, an end section 110 having a flange 111 is secured to flange 35 by means of bolts 52. A suitable gasket 112 is interposed between flanges 35 and 111 to insure a leak-proof joint. A downwardly extending auxiliary air conduit 44 and an outlet conduit 18 are integrally formed on each end section 110 and connected to each conduit 44 is an air intake cleaner 54. A butterfly valve 41, adapted to close-off passage 43, is journaled for rotation upon a shaft 113. The ends of shaft 113 are supported in the walls of section 110 and held against rotation by squaring one end, or in any other suitable manner.

Valve 41 is provided with a centrally disposed ear 114 (Fig. 7) in which actuating pin 115 is supported. A boss 116 is formed on ear 114 and provided with an aperture 117 (Fig. 8) through which one end of coil spring 118 is inserted. A set screw 119 threaded into the end of boss 116 secures the end of spring 118 in position. The opposite end of spring 118 is secured to a pin 121 mounted in an aperture 122 in the end wall 123 of member 110, or is otherwise suitably secured. Spring 118 is normally under tension between boss 116 and pin 121, and due to the location of boss 116 below the center of shaft 113, the spring biases valve 41 to closed position.

An air inlet valve 46 is journaled on shaft or rod 124 in conduit 44. The ends of shaft 124 are non-rotatably supported in the walls of conduit 44 in any suitable manner. A centrally disposed ear 125 having a boss 126 secured thereto is integrally formed on valve 46. A suitable aperture 127 adapted to receive one end of a coil spring 128 is formed in boss 126, and set screw 129 holds spring 128 in aperture 127. The other end of spring 128 is secured to a screw 131 threaded into the wall of conduit 44. Boss 126 is positioned upon ear 125 in such a manner that spring 128 normally biases valve 46 to its closed position.

A second ear 132 is formed on the opposite face of valve 46 and is provided with an actuating pin 133.

Section 110 opposite outlet 18 is provided with an opening 134 (Fig. 8) which is closed by a cover plate 135. Plate 135 is retained in sealing relation upon a gasket 136 interposed between the end of conduit 134 and the face 137 of cover 135 by means of machine screws 138 (Fig. 6). Cover plate 135 is preferably provided with an eccentrically disposed boss 139 in which a short shaft 141 is journaled. Shaft 141 supports a cam member 142 on its inner end.

Cam 142 is provided with a hub 143 secured for rotation with shaft 141 by means of a pin 144. Cam 142 is further provided with an arm 145

which is adapted to engage pin 133 of valve 46 to rotate valve 46 to its open position against the influence of spring 128. A second arm 146 is formed integrally with cam 142 and is adapted to engage pin 115 of valve 41 to open valve 41 5 against the action of spring 118.

Cam 142 and shaft 141 are actuated through a linkage, that will now be described, by operation of the vehicle accelerator 147 through one end of a cross shaft 148 which passes across in front of the motor to the left-hand side thereof where the operator is seated. Rigidly secured to and rotatable with the opposite end of shaft 148 is a rocker arm 149 secured to shaft 148 by means of a stud 151 which draws the ears 152, integrally formed on split hub 153 of the rocker arm, together around the end of shaft 148.

Arm 154 is provided at one end with a pin 156 to which a clevis 157 is rotatably secured. Throttle actuating rod 158 is adjustably connected to 20 clevis 157 at 159. The opposite end of rod 158 is adjustably received in a clevis 161 which is slidably associated with pin 69 of throttle operating lever 55 by means of a lost motion slot 162. An arm 163 is secured to rod 158 by a set screw 25 164 at any convenient point, and a suitable coil spring 165 is secured at one end to arm 163 and at its other end to a bracket 166 secured in any suitable manner on the engine. Spring 165 normally biases rod 158 to the right, as seen in Figure 6, to hold lever 55 in the position corresponding to the closed position of throttle valve 21. Spring 165 also urges rocker arm 149 and the accelerator 147 toward the positions they assume 30 when the engine is operated under closed throttle conditions.

At its upper end rocker arm 149 carries pin 167 which connects actuating rod 168 to arm 149 through a lost motion slot 169 of the clevis 171. Clevis 171 adjustably receives one end of rod 163, 40 and the other end of rod 168 is adjustably received in a clevis 172 which is connected by means of a pin 173 to one arm of bell-crank 174 which in turn is non-rotatably secured to the outer end of shaft 141.

Secured in the end of the opposite arm of bell-crank 174 is a pin 175, which has connected to it a clevis 176. Clevis 176 adjustably receives one end of a tie rod 177 connected by means of a similar pin 175' and clevis 176' at its other end to the end of lever 178 secured to shaft 141'. Shaft 141' operates valves 41 and 46 provided at this end of the manifold. As heretofore pointed out, the valves and operating mechanisms in the end sections 110 are similar. However, since 55 valves 46 and 41 have been reversed in the left hand end section with relation to cam 142 the cam has been reversed and the lever 178 designed to impart clockwise rotation thereto.

Bell-crank 174 and lever 178 are each provided with an ear 179 carrying a pin 181 upon which one end of a coil spring 182 is secured. The other end of each spring 182 is secured to a pin 183 or other suitable projection formed on the side wall of each section 110. As shown in Figure 6, 65 pins 181 are positioned just below the centers of shafts 141 with the valves 41 and 46 in idling position.

With the operating mechanism in its idling or closed throttle position, as shown in Figure 3, 70 when the accelerator is actuated, shaft 148 and rocker arm 149 rotate in a clockwise direction, moving actuating rod 158 to the left, as viewed in Figure 6, but the lever 55 will not be actuated due to the sliding of pin 69 in slot 162. Throttle 75

valve 21 will therefore remain closed during the initial operation of the vehicle accelerator.

At the same time that rod 168 is moved to the left actuating rod 168 will be moved to the right 5 since pin 167 is in the extreme right-hand end of slot 169. This movement of rod 168 causes a counter-clockwise movement of arm 174 and clockwise movement of lever 178. Pins 181 as a consequence rotate past their dead center position 10 at which time springs 182, which are under tension at all times, snap arms 174 and 178, shafts 141 and cams 142 in counter-clockwise and clockwise directions respectively at opposite ends of the manifold. This snap action is made 15 possible by slot 169 which is of sufficient length to permit cams 142 to rotate to their open throttle position after pins 181 pass dead center without affecting arm 149.

Cams 142, due to their sudden rotation under 20 the influence of springs 182, permit springs 128 to turn valves 46 to their closed positions. Immediately upon the closing of valves 46 arms 145 of cams 142 move out of contact with pins 133 and arms 146 contact pins 115 of valves 41 and 25 open said valves against the action of springs 118. This entire actuation of cam 142 takes place between the initial actuation of the accelerator and the completion of the snap action under the influence of spring 182. Springs 182 30 are of greater strength than springs 118 in order that cams 142 may rotate valves 41 to their open position.

The successive movement of valves 41 and 46 35 from closed throttle position to open throttle position takes place prior to any movement of throttle valve 21 and as a consequence the engine passes through a period wherein it idles in a conventional manner prior to being accelerated and while valves 41 and 46 are being actuated. This period 40 of conventional idling, however, is only momentary since the accelerator is continuously pressed toward its open position and the gassing incident to conventional idling is not obtained. Throughout further actuation of accelerator 141 valve 21 is 45 actuated in conventional manner. Since the action of spring 182 and arms 174 has moved rod 168 to the right so that pin 167 rests in the extreme left-hand end of slot 169 this continued clockwise rotation of shaft 148 and arm 149 under 50 the influence of accelerator 147 will not cause any movement of rod 168 or cams 142.

In decelerating the engine, the lost motion connection provided by slot 169 permits the throttle valve 21 to be closed completely prior to operation 55 of rod 168. After valve 21 is closed pin 167 will engage the left-hand end of slot 169 causing arm 174 to rotate in a clockwise direction. This clockwise rotation of arm 174 causes cams 142 to restore the parts to idling position, valves 41, 60 being first closed by the action of springs 128, and then valves 46 are opened by the action of springs 118. The operation of the valves during deceleration is in reverse order from their operation during acceleration.

65 It is therefore apparent that during idling, accelerating and decelerating operations this form of invention prevents obnoxious gassing, purges the cylinders and exhaust system with air, and saves fuel without interfering with the normal 70 acceleration of the engine when desired, in the same way that these functions are secured in the form of invention shown in Figures 1 to 5.

In Figure 9 of the drawings a further modification of the invention is disclosed embodying an 75 automatic device for operating the valves 41 and

46. In this form of the invention the manifold is manufactured in two sections 201 and 202. Suitable flanges 203 are secured in assembled relation with a gasket 204 therebetween by means of bolts 205. Section 201 supplies fuel to cylinders numbered 4, 5, and 6 through outlet connections 206, 207 and 208, while section 202 supplies cylinders numbered 1, 2 and 3 through outlet connections 209, 211, and 212. Each outlet connection is independent of every other outlet 10 and is provided with an attachment flange 213.

Section 202 is furthermore provided with an auxiliary air inlet conduit 44 upon which air cleaner 54 is secured in the manner and for the purpose described in connection with the previous forms of the invention. A single shut-off valve 41 and air control valve 46 with an operating spring and cam mechanism identical with the construction to the valves and operating mechanism therefore shown in Figures 7 and 8 20 are utilized in this form of the invention. Since the details of these valves and the operating mechanism therefore have been described in detail, it will not be here repeated.

Only one set of valves 41 and 46 is utilized in 25 the present form of invention. These valves are mounted in section 202 adjacent flange 203, as shown, and operation thereof will cut cylinders 1, 2, and 3 off from the fuel supply and will connect them to atmosphere through cleaner 54, 30 since the control valves are disposed between said cylinders and the throttle valve 21. As a result of this arrangement cylinders 4, 5 and 6 will be supplied with fuel mixture from the carburetor during idling and deceleration of the engine 35 while cylinders 1, 2 and 3 will alternately compress, expand and discharge air. As the firing order of the engine utilized with this form of the invention is 1-5-3-6-2-4, when cylinders 1, 2 and 3 are cut out, uniform firing takes 40 place since alternate cylinders will fire.

The outer end of cam shaft 141 is connected to a bell-crank 214 which is a reproduction of the lower part of rocker arm 174 of Figure 6. Ear 178 thereof is provided with pin 181 which 45 receives one end of a coil spring 182a. Spring 182a differs from spring 182 only in length. The opposite end of spring 182a is secured to pin 183 on the side wall of section 202.

Pin 178 carried by lever 214 receives a clevis 50 215, preferably having a lost motion slot 216 therein. Although slot 216 is preferably provided, it will be understood that such an arrangement is not essential to satisfactory operation of the present modification. Clevis 215 is formed 55 on one end of a rod or link 217. The other end of link 217 is connected by means of an adjustable clevis 218 to a pin 219 carried by rod 220. Rod 220 is threaded to receive nuts 221 and 222 between which a flexible diaphragm 223 of a 60 pressure responsive actuator 224, secured in any suitable manner to section 201, is positioned. The edges of nuts 221 and 222, which contact diaphragm 223, are suitably rounded to prevent cutting of the diaphragm. If desired suitable 65 plates, of well-known construction rounded at their edges, may be disposed between diaphragm 223 and nuts 221 and 222 instead of rounding the edges of said nuts.

The outer edges of diaphragm 223 are secured 70 between an annular flange 225 formed on housing 226 and a securing ring 227 by means of nut and bolt assemblies 228. Housing 226 is of dished form and is provided with a centrally disposed recessed boss 229, the recess of which receives 75

one end of coil spring 231. The opposite end of spring 231 surrounds the protruding end 232 of rod 220 and abuts nut 222. The other end of spring 231 abuts the end wall 233 of boss 229. 5 Spring 231 is placed under sufficient compression to force diaphragm 223 and link 217 to the right (as pressures are holding the diaphragm in position shown).

Chamber 234 formed between diaphragm 223 10 and housing 228 is connected to the interior of manifold section 201 by means of a conduit 235. Due to this connection chamber 234 is subjected to the pressures existing in the intake manifold section 201. These pressures, as they vary, cause 15 diaphragm 223 and the parts connected thereto to move in a well-known manner. Since the manifold pressure never exceeds atmospheric pressure, diaphragm 223 is urged to its normal position by spring 231 alone at all times. Therefore, link 216, lever 214 and valves 41 and 46 20 will assume their open throttle or inoperative positions with valve 41 open and valve 46 closed, until the pressure in section 201 falls below a predetermined value dependent upon the compression of spring 231.

Since it is desirable for the engine upon which the present device is used to always be capable of ready acceleration in the most efficient manner, the tension of spring 231 is adjusted so that 25 the intake vacuum pressure incident to idling speed of the engine is just sufficient to overcome spring 231 and to cause the closing of valve 41 and the opening of valve 46. It is because of this adjustment that the adjustable clevis 218 30 heretofore described is provided.

To effect the desired adjustment, with the device of the present invention in place and valves 41 and 46 properly adjusted, link 217 is backed off from clevis 218 until lever 214 assumes 40 its operative position with pin 181 below the center line of shaft 141. The engine is then started and adjusted to its proper idling speed. Then with the engine idling link 217 is adjusted in clevis 218 until pin 181 is raised to a point 45 just below the center of shaft 141. Since the intake vacuum in section 201 at this time is 8 inches, as heretofore pointed out in connection with the idling speed of the modification of Figures 1-5, it will be seen that the pressure operator 224 is adjusted to function when the vacuum in section 201 drops to 8 inches or below.

Assuming that the engine is operating at idling speed and the operator 224 is in the position shown in Figure 9, upon actuation of the accelerator the lever 55 and valve 21, due to movement of rod 158 to the left as shown in Figure 9, will be rotated in a counter-clockwise direction and opened. As valve 21 opens, the pressure in section 201 and in chamber 234 increases, and spring 60 231 through diaphragm 223 and link 217 moves lever 214 in a counter-clockwise direction against the influence of spring 182a until pin 181 reaches a point just above the center of shaft 141. At this moment spring 182a becomes effective to 65 rotate lever 214 in a counter-clockwise direction and snaps lever 214 into its open throttle or normal engine operating position in the manner heretofore described in connection with Figures 6 to 8. This snap action is permitted due to lost motion slot 216.

As heretofore pointed out lever 214 is connected for rotation with shaft 141 which carries cam 142. Cam 142 in turn operates valves 41 and 46 in the same manner described in the modification shown in Figures 6 to 8. It will therefore 75

be seen that lever 214, due to its counter-clockwise rotation under influence of spring 231 and later spring 182a, will close valve 46 and open valve 41 to thereby connect cylinders 1, 2, and 3 to the fuel supply. Due to expansion of spring 231, pin 173 will be disposed in the left-hand end 5 of slot 216. Since the accelerator will, under ordinary operating conditions, be continuously actuated to accelerate the vehicle, the engine will not idle in the conventional manner for any 10 length of time and the undesirable gassing and incomplete combustion accompanying conventional idling is eliminated.

To decelerate the vehicle and engine, the accelerator is released upon closing of valve 21. The 15 manifold pressure in sections 201 and 202 and in chamber 234 is lowered, causing diaphragm 223 and link 217 to move to the left in Figure 9 under the influence of atmospheric pressure on the outside of the diaphragm and against the 20 resistance offered by spring 231. The initial movement of link 217 first takes up the lost motion in slot 216 and then actuates pin 173 to impart clockwise rotation to lever 214 until pin 181 passes below the center of shaft 141. As soon 25 as pin 181 reaches this off center position spring 182a will snap the lever 214 and valves 41 and 46 into their idling position with pin 173 in the extreme left end of slot 216. When the intake pressure within section 201 drops below the normal idling pressure slot 216 will permit further 30 diaphragm movement as shown in Figure 9 to provide for a practical margin of adjustment.

In this form of the invention all of the advantages of the constructions shown in Figures 35 1 to 8 are secured in the way of freedom from obnoxious gases, fuel economy and air purging during idling and deceleration of the engine, and the following further desirable operation is secured. To accelerate a motor vehicle from rest 40 to a desired running speed normally requires the full motor power output, but to maintain the running speed after acceleration for ordinary operation requires only a comparatively small part of the motor horsepower. It is now the common 45 practice to accelerate to the desired running speed, and then to throttle the engine in order to effect the necessary reduction of horsepower to prevent further acceleration. This throttling of the engine, however, causes a reduction of the 50 compression with reference to atmospheric pressure and an increase in the manifold vacuum, and as a consequence the motor cylinders normally operate in an inefficient manner under such conditions. Under such conditions with the 55 present invention installed on the engine when the manifold pressure reaches idling pressure as very frequently occurs, diaphragm 223 will be actuated to close valve 46 and to open valve 41, and the engine will then operate on half of its cylinders 60 under very efficient compression and combustion conditions. It will, therefore, be appreciated that the present invention greatly improves the operation of the internal combustion engine during 65 all phases of its operation.

While the automatic operation of valves 41 and 46 has been described in connection with an engine having separate manifold outlets for each branch, it is to be understood that it may be utilized in conjunction with other type manifolds 70 with very slight alterations. For example the operator 224 may be utilized on the manifold shown in Figures 6-9 by merely connecting rocker arm 174 to link 217, removing link 168 and the upper section of rocker arm 148, and connecting con- 75

duit 235 to section 34a of the manifold. By means of like slight changes the automatic actuator may be applied to the modification of Figures 1-5. The claims are therefore intended to cover all of the above suggested uses and all obvious equivalents thereof.

While it is desirable to utilize the toggle spring 182a with the automatic operator very satisfactory results may be obtained without the use thereof. In the event that it is found desirable to eliminate the snap action the lost motion connection provided by clevis 215 may be replaced by a positive connection and the spring 231 may be relied upon to actuate arm 214 in one direction and the vacuum pressure will cause operation thereof in the opposite direction.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

- 30 1. In an apparatus for effecting fuel economies in a multi-cylinder engine, means operative when said engine is idling or at or below light load for increasing the compression in certain of said cylinders to increase the efficiency of combustion of the fuel fed thereto, and means to impose a load upon the remaining cylinders to increase the load upon the cylinders being fueled, said plurality of means being arranged to be sequentially operated.
- 40 2. In an apparatus for effecting fuel economies and preventing gassing in the operation of a multi-cylinder internal combustion engine, particularly at idling speeds and at or below light load conditions, means for increasing the compression in certain of said cylinders to increase the efficiency of combustion of the fuel fed thereto, means to impose a load upon the remaining cylinders to increase the load upon the cylinders being fueled, and means to render said latter means inoperative prior to said first means when said engine is desired to operate at a higher speed or under increased load.
- 50 3. In an apparatus for effecting fuel economies and preventing gassing in the operation of a multi-cylinder internal combustion engine, an intake manifold having a fuel inlet and a plurality of outlets to said cylinders, means to restrict the flow of fuel from said inlet to a predetermined number of outlets to restrict the feed of fuel to certain of said cylinders to increase the compression therein and increase the efficiency of combustion of the fuel fed thereto, means to permit a relatively unrestricted flow of inert gas to the remaining cylinders to increase the load upon said cylinders being fueled, and means to close said latter means prior to opening said fuel-restricting means whereby a relatively high vacuum is created in said unfueled cylinders prior to the admission of fuel thereto.
- 60 4. In an apparatus for effecting fuel economies and preventing gassing in the operation of a multi-cylinder internal combustion engine, a throttle, means operated by movement of said throttle toward closed position for increasing the compression in certain of said cylinders to in-

crease the efficiency of combustion of the fuel fed thereto, means operated by movement of said throttle toward closed position to impose a load upon the remaining cylinders to increase the load upon the cylinders being fueled, said plurality of means being connected to said throttle in a manner whereby on moving said throttle toward open position, said latter means is rendered inoperative prior to said throttle operated means.

5 5. In an apparatus for effecting fuel economies and preventing gassing in the operation of a multi-cylinder internal combustion engine, means for increasing the compression in certain of said cylinders to increase the efficiency of combustion of the fuel fed thereto, means to impose a load upon the remaining cylinders to increase the load upon the cylinders being fueled, and means responsive to vacuum conditions in the inlets of said cylinders to operate said means.

10 6. In an apparatus for effecting fuel economies and preventing gassing in the operation of a multi-cylinder internal combustion engine particularly at idling speeds and at or below light load conditions, means for increasing the compression in certain of said cylinders to increase the efficiency of combustion of the fuel fed thereto, means to impose a load upon the remaining cylinders to increase the load upon the cylinders being fueled, and means responsive to the vacuum conditions in the inlet to said cylinders to sequentially operate said plurality of means.

15 7. In an apparatus for effecting fuel economies in the operation of multi-cylinder internal combustion engines particularly when operating at idling and at or below light load conditions, means having a fuel inlet and outlets to the several cylinders, a valve in said means between said fuel inlet and an outlet, a second inlet in said means between said valve and said outlet, a valve in said second inlet, and means responsive to the vacuum in said outlets to the several cylinders for operating said valves.

20 8. In an apparatus for effecting fuel economies in the operation of multi-cylinder internal combustion engines particularly when operating at idling and at or below light load conditions, a manifold with a fuel inlet and outlets to the several cylinders, a throttle valve in said fuel inlet, a second valve in said manifold between said throttle valve and an outlet, a second inlet in said manifold between said valve and said outlet for the introduction of a relatively inert gas, a valve in said second inlet, and means associated with said throttle valve to close said valve in said second inlet and subsequently open said second valve.

25 9. The combination as claimed in claim 8 wherein said throttle valve is opened subsequently to the opening of said second valve.

30 10. In an apparatus for effecting fuel economies in the operation of multi-cylinder internal combustion engines, particularly at idling speeds and at or below light load conditions, comprising a manifold having a fuel inlet and a plurality of outlets to the several cylinders, of fluid inlet, means associated with said manifold to interrupt the flow of fuel to certain of said outlets while permitting a free flow of fuel to the remaining outlets, means to permit a free flow of a relatively inert gas through said fluid inlet to said certain outlets under certain conditions, and means responsive to vacuum conditions in said manifold for operating said means.

35 11. In an apparatus for effecting economies

- in the operation of multi-cylinder internal combustion engines particularly at idling speeds and at or below light load conditions comprising an intake manifold having a fuel inlet and a series 5 of outlets to the several cylinders, a throttle valve in said fuel inlet, a valve in said manifold between said fuel inlet and an outlet, means to normally bias said valve to closed position, an inlet for relatively inert fluid between said 10 valve and said outlet, a valve located in said inlet, means to normally bias said valve to closed position, a shaft adjacent said last-mentioned valves, an actuator on the inner end of said shaft arranged to sequentially operate said valves 15 against said biasing means, a lever on the outer end of said shaft to operate said actuator, a spring associated with said lever to effect a snap action to the movement thereof in rotating said shaft, a rod arranged to operate said lever, a 20 rocker arm mounted for rotation and secured at one end to said lever, a throttle control rod secured to the opposite end of said rocker arm, a lost motion connection between said lever and said rocker arm to permit a snap action of said lever, a second lost motion connection between said throttle valve and said rocker arm to permit operation of said manifold valve and inert fluid inlet valve prior to operation of said throttle valve.
- 30 12. In a method of operating a multi-cylinder combustion engine to effect economies therein particularly when operating at idling speeds and at or below light loads, the steps which comprise confining fuel flow to certain of the cylinders in accordance with a predetermined position of the throttle of the engine to increase the compression therein and increase the efficiency of combustion of the fuel fed to said cylinders, and subsequently increasing the load upon 35 said cylinders in accordance with a predetermined position of said throttle by permitting an unrestricted flow of a relatively inert gas to the remaining cylinders.
13. In a method of operating a multi-cylinder 40 internal combustion engine to effect economies therein particularly when operating at idling
- speeds and at or below light loads which comprises the steps of confining the feed of fuel to certain of said cylinders, freely admitting a relatively inert gas to the remaining cylinders when the pressure in the intake of said cylinders reaches a predetermined value, and supplying fuel to all of said cylinders when said intake pressure rises above said predetermined value. 5
14. In an apparatus for effecting fuel economies in a multi-cylinder internal combustion 10 engine, means effective at predetermined throttle positions for increasing the compression in certain of said cylinders to increase the efficiency of combustion of the fuel fed thereto, means to exclude fuel from and unrestrictedly 15 feed a relatively non-combustible gas to the remaining cylinders to impose loads thereon and increase the load upon the cylinders being fueled, and means to dilute the exhaust gases from said cylinders being fueled with non-combustible gas. 20
15. In an apparatus for effecting fuel economies in the operation of multi-cylinder internal combustion engines particularly when operating at idling speeds and at or below light load conditions, means having a fuel inlet and outlets to 25 discharge fuel to the several cylinders, a valve in said means between two of said outlets, an inlet designed to admit inert gas in said means between said valve and one of said outlets, a valve in said last mentioned inlet and means for sequentially operating said valves. 30
16. In an apparatus for effecting fuel economies in the operation of multi-cylinder internal combustion engines, particularly when operating at idling and at or below light load conditions, 35 means having a fuel inlet and outlets to discharge fuel to the several cylinders, a valve in said inlet, a pair of valves in said means between said fuel inlet and certain of said outlets, a fluid inlet in said means between each of said last mentioned valves and said outlet, a valve in said fluid inlets and means associated with said fuel inlet valve for sequentially operating said latter valves. 40
